(57) **CLAIM**

The ornamental design for a multiple port beam bracket, as shown and described.

DESCRIPTION

FIG. 1 is a front left top perspective view of a multiple port beam bracket in accordance with the present invention.

FIG. 2 is another front left top perspective view showing the multiple port beam bracket of FIG. 1.

FIG. 3 is a front left bottom perspective view showing the multiple port beam bracket of FIG. 1.

FIG. 4 is a front left top perspective view showing the multiple port beam bracket of FIG. 1.

FIG. 5 is a front elevation view showing the multiple port beam bracket of FIG. 1, with the rear being a mirror image thereof.

FIG. 6 is a left elevation view showing the multiple port beam bracket of FIG. 1.

FIG. 7 is a right elevation view showing the multiple port beam bracket of FIG. 1.

FIG. 8 is a top plan view showing the multiple port beam bracket of FIG. 1.

FIG. 9 is a bottom plan view showing the multiple port beam bracket of FIG. 1.

FIG. 10 is a front left top perspective view of another embodiment of a multiple port beam bracket in accordance with the present invention.

FIG. 11 is another front left top perspective view showing the multiple port beam bracket of FIG. 10.

FIG. 12 is a front left bottom perspective view showing the multiple port beam bracket of FIG. 10.

FIG. 13 is a front left top perspective view showing the multiple port beam bracket of FIG. 10.

FIG. 14 is a front elevation view showing the multiple port beam bracket of FIG. 10.

FIG. 15 is a rear elevation view showing the multiple port beam bracket of FIG. 10.

FIG. 16 is a left elevation view showing the multiple port beam bracket of FIG. 10, with the right being a mirror image thereof.

FIG. 17 is a top plan view showing the multiple port beam bracket of FIG. 10; and,

FIG. 18 is a bottom plan view showing the multiple port beam bracket of FIG. 10.

(Continued)

The broken lines shown in the Figures depict environmental subject matter only and are not part of the claimed design.
